UNITED STATES PATENT OFFICE.

LEWIS F. RICHARDS, OF MELVILLE, NEW JERSEY, ASSIGNOR TO AUBRY SISTERS, OF NEW YORK, N. Y., A CORPORATION OF NEW YORK.

DESIGN FOR A BOTTLE.

41,700.

Specification for Design.

Patented Aug. 22, 1911.

Application filed May 19, 1911. Serial No. 628,252. Term of patent 3½ years.

To all whom it may concern:

Be it known that I, LEWIS F. RICHARDS, a citizen of the United States of America, and resident of Melville, in the county of Cumberland and State of New Jersey, have invented a certain new, original, and ornamental Design in Bottles, of which the following is a specification.

My improved design consists of an elongated bottle having a square bottom, beveled in two directions, with a rim around the same. The body-portion of the bottle is flat with beveled edges at the four corners. These beveled edges gradually merge into a curved cap which pass around the bottle, and these pass into a curved annular por-

tion having a rim and then another cylindrical portion, on top of which fits a double beveled portion having a very sharp edge.

In the accompanying drawing, Figure 1 shows a front-view and Fig. 2 a top-view.

I claim:

The ornamental design for a bottle, as shown and described.

In testimony, that I claim the foregoing as my invention, I have signed my name in presence of two subscribing witnesses.

LEWIS F. RICHARDS.

Witnesses:

JOHN MURTAGH,
L. M. DORMAN.
